UNITED STATES PATENT OFFICE.

FLOYD EUBANKS, OF PASADENA, CALIFORNIA, ASSIGNOR OF ONE-HALF TO ROBERT E. MCCOLLOR, OF PASADENA, CALIFORNIA.

KEY GUIDE.

Application filed May 6, 1925. Serial No. 28,439.

My invention relates to attachments for door locks and more particularly to a guide for guiding the key into the keyhole of the lock.

5 It is an object of the invention to provide a key guide formed from a single piece of resilient metal which may be easily and securely attached to the keyhole without the necessity of making alterations.

10 A further object of the invention is to provide a device of the above-mentioned character which is simple and durable in construction, efficient in use and inexpensive to manufacture.

15 Other objects and advantages of the invention will be apparent during the course of the following description.

In the accompanying drawing, forming a part of this specification and in which like numerals are employed to designate like parts throughout the same,

20 Fig. 1, is a fragmentary perspective view of a door and lock with my invention applied thereto,

25 Fig. 2, is a perspective view of the guide, Fig. 3, is a longitudinal sectional view of the guide applied to the escutcheon plate, and,

30 Fig. 4, is a plan view showing the blank from which the guide is formed.

In the drawing, wherein for the purpose of illustration I have shown a preferred embodiment of my invention, the numeral 5 designates an escutcheon plate of a conventional type of door lock having the usual keyhole opening 6 to which my guide is attached.

35 The guide is denoted in general by the numeral 7 being formed from a longitudinal strip of sheet metal 8 bent intermediate its ends, to form a substantially V-shaped body, the ends of which are tapered and slightly curved upwardly, as at 9. An upwardly curved tang 10 extends laterally from one edge of the body at its apex and

40 is adapted to engage the peripheral edge of the keyhole 6 at the top. The sides of the body are connected with the keyhole by the

arms 11 formed integral with the same edge and bent inwardly, at right angles to the sides, towards each other, having their free extremities curved to form hooks 12 adapted to engage the peripheral edges of the keyhole at the sides. The body is formed of spring metal, so that the tension of the sides will hold the arms 11 in engagement with the keyhole, but may be easily compressed to release the arms when removing or affixing the guide in place. It will be observed that the body on each side of the arms and tang are slightly notched, as at 13, so that when the arms are bent the body will lie flush with the surface of the escutcheon plate.

45 As more clearly shown in Fig. 4, the guide is formed from a single piece of material, the arms 11 extending from one edge of the strip at an angle, so that when the strip is bent into proper shape the arms will be disposed on a horizontal plane, whereby the resiliency of the sides will hold the arms in firm engagement with the keyhole.

50 In use, it will be seen that a keyhole equipped with the guide may be easily found in the dark, since the key upon contacting with the guide will be guided into the keyhole.

55 It is to be understood that the form of my invention herewith shown and described is to be taken as a preferred example of the same and that certain changes in the shape, size and arrangement of the parts may be 60 made without departing from the spirit of the invention within the scope of the subjoined claims.

65 Having thus described my invention, I claim:

1. A key guide comprising a V-shaped body formed from a single strip of resilient metal, and arms extending inwardly from the sides of said body movable through the resiliency of the body to engage an opening for connecting said body thereto.

70 2. The combination with an escutcheon plate having a keyhole opening, of a V-shaped body formed from a single strip of

material bent intermediate its ends, a curved tang extending laterally from the apex of said body, and arms extending inwardly from the sides of said body, said tang and arms being adapted to engage the peripheral edge of said keyhole opening.

3. The combination with an escutcheon plate having a keyhole opening, of an ex-

pansible V-shaped body, and arms extending inwardly from the sides of said body, adapted to be held in engagement with said opening through the expansion of said body.

In testimony whereof I affix my signature.

FLOYD EUBANKS.
